Primary Examiner — Cynthia R Underwood

(57) **CLAIM**

The ornamental design for a dish as shown and described.

DESCRIPTION

1. Dish

1.1 : Perspective

1.2 : Top

1.3 : Front

The design is related to a rectangular dish or serving plate and narrow sides of the plate are slightly raised; Inside the plate there are geometric shapes starting from the narrow side parts of the plate and continuing towards the centre of the plate; The four corners of the rectangular plate are slightly rounded.
